(57) **CLAIM**

The ornamental design for a travel bottle, as shown and described.

DESCRIPTION

FIG. 1 is a perspective view of a travel bottle showing my new design;

FIG. 2 is a top plan view thereof;

FIG. 3 is a rear elevational view thereof;

FIG. 4 is a bottom plan view thereof;

FIG. 5 is a right side view thereof;

FIG. 6 is a front elevational view thereof; and,

FIG. 7 is a left side view thereof.

The broken lines depict elements of the travel bottle that form no part of the claimed design. The unshaded areas within the bottom end and each oblong region containing broken lines likewise form no part of the claimed design.
